HIGH POWER TUBE

Louis A. Gebhard, Washington, D. C.

Application March 22, 1933, Serial No. 662,111

5 Claims. (Cl. 250—27.5)

(Granted under the act of March 3, 1883, as
amended April 30, 1928; 370 O. G. 757)

My invention relates broadly to high power electron tube systems and more particularly to a construction of double demountable electron tube of the four element type.

5 One of the objects of my invention is to provide a high power double electron tube which includes a renewable cathode, control grid, screen grid and anode assembled in a demountable relation.

10 Another object of my invention is to provide a construction of double demountable four element electron tube in which the control grids in the double tube are telescopically engaged in a position intermediate the length of the tube by an insulation member mounted within the vessel which encloses the tube electrodes and concentrically of a renewable screen grid electrode.

15 Still another object of my invention is to provide a construction of demountable electron tube arranged for connection in a symmetrical amplification circuit in which a single screen grid is employed for electrostatically shielding a double group of tube electrodes.

20 25 A further object of my invention is to provide a construction of double demountable electron tube wherein a pair of control grids are insulatingly supported from opposite end plates and adapted to be axially aligned and insulatingly interconnected by a telescopic movement in a position concentrically related to a removable screen grid disposed concentrically with respect to the anodes of the double demountable tube.

30 35 A still further object of my invention is to provide a construction of four element demountable tube in which separable electrostatic shields are connectible with opposite ends of one of the elements in the double electron tube structure.

35 40 Still another object of my invention is to provide a construction of screen grid demountable electron tube in which a single screen grid is mounted in concentric relation to separate sets of control grid and anode electrodes with respect to which a renewable cathode element is axially related.

45 Other and further objects of my invention reside in the construction of a double demountable screen grid tube as set forth more fully in the specification hereinafter following by reference to the accompanying drawings, wherein:

50 55 Figure 1 is a side elevation of the double demountable screen grid tube of my invention with the securing means broken away and with the central portion of the tube broken away and illustrated in section for indicating the adjacent

ends of the two anodes and the screen grid therein; Fig. 2 is a vertical cross-sectional view taken through the double demountable screen grid tube of my invention, portions of the screen appearing in the rear being omitted in this and other figures to avoid confusion; Fig. 3 is a transverse cross-sectional view taken through the electron tube of my invention on line 3—3 of Fig. 2; Fig. 4 is a fragmentary cross-sectional view in enlarged form showing the upper end of the demountable tube elements of my invention and illustrating the manner of establishing electrical connection to the upper control grid; Fig. 5 is a vertical sectional view of the lower portion of the double demountable screen grid tube of my invention and illustrating the manner of establishing electrical connection to the lower control grid in the tube; Fig. 6 is a cross-sectional view of the upper portion of the double demountable electron tube taken at ninety degrees with respect to the view of Fig. 4 and illustrating the connection for the screen grid electrode; Fig. 7 is a fragmentary cross-sectional view of the lower portion of the tube taken at ninety degrees with respect to the view of Fig. 5 and showing the connection to the screen grid for the lower set of tube electrodes; Fig. 8 is a perspective view of the removable mounting means for the screen grid electrode in the demountable tube; Figs. 9, 10 and 11 illustrate modified forms of airtight joints which may be used in the construction of my invention for insuring an airtight closure within the tube of my invention; and Fig. 12 illustrates a modified form of insulated securing means which may be employed for compressing the end plates upon the ends of the insulated sleeves which are secured over the tubular anode structures in the double demountable tube of my invention.

40 45 My invention provides a construction of double demountable electron tube of the screen grid type wherein the parts may be readily disassembled for renewal of deteriorated elements and the replaceable elements restored to position and the tube re-pumped to provide that degree of vacuum required for electronic operation. The electrodes of the tube are compactly assembled, and yet, insulatingly spaced and supported in such relation that breakdown is avoided. The tube comprises end plate members which insulatingly support control grid electrodes of cylindrical structure. The control grid electrodes are telescopically engaged at their adjoining ends over an insulated sleeve element which maintains the control grids in axial alignment. Terminals for each of the

control grids are supported in insulating relation on each of the end plates. The same screen grid is employed for both sets of electrodes in the tube. The structure of the screen grid is such that the 5 cylindrical ends thereof may be interengaged on sleeve members insulatingly supported from the end plates. These sleeve members each include laterally extending electrostatic shields. The cylindrical ends of the screen grid slidably fit over 10 the sleeves insulatingly mounted on the end plates and enable the screen grid to be concentrically disposed within the tube. The anodes for the double tube are each fluid cooled. Sleeve members and gaskets of insulation material are employed 15 for spacially mounting the sets of tube electrodes. Various means are provided for securing the double set of electrodes in assembled relation for permitting a vacuum to be maintained in the closed vessel formed by the electrodes.

20 The double demountable screen grid tube of my invention has many economies over electron tubes heretofore known in the art and is not subject to the economic waste encountered in tubes heretofore known.

25 Referring to the drawings in detail, the filament 1 of the tube extends longitudinally through the center of the tube. Two control grids 2 and 2' surround the filament. A single screen grid 3 surrounds the control grids and extends to the 30 both ends of the tube. Two anodes 4 and 4' are symmetrically disposed with respect to the other elements and surround the screen grid 3.

35 The filament 1 is secured at its ends by mountings 5 and 5'. The construction of and method of fluid cooling these mountings and the manner in which expansion of the filament is compensated is set forth more fully in my Patent 1,993,724, granted March 5, 1935. The mountings are supported from end plates 6 and 6'. The 40 filament terminals are shown at 5a and 5a'.

45 The control grids 2 and 2' are supported respectively from end plates 6 and 6' in a demountable assembly. The grids are supported and aligned at the center by means of insulating member 7. This insulator is made of magnesium silicate or a combination of magnesium and aluminum silicate having low radio frequency loss and good heat resisting qualities. All other insulating parts of the tube are preferably made of 50 this material. Insulator 7 also tends to shield the electron emission from that portion of the filament adjacent to it, thus preventing a flow of electrons which would otherwise be used in carrying an uncontrolled current to the anode. The 55 efficiency of the tube from this standpoint is thus improved due to the location of insulator 7. The rings 8 and 8' slip over shoulders on insulator 7, thus making assembly of the tube very easy. The control grid terminals are shown at 2a and 2a' 60 insulatingly mounted on end plates 6 and 6'.

65 The screen grid 3 shields the control grids 2 and 2' from the anodes. By making the screen grid continuous from one end of the tube to the other, very efficient shielding is obtained. The fact that the end plates 6 and 6' are of metal 70 also serves to shield the control grids as does the extension of the screen grid at its ends, as shown at 9 and 9'. The mounting of the ends of the screen grid 3, with respect to the end plates 6 and 6' respectively, is accomplished by members disposed in ninety degree spaced relation with respect to the members which support the control grids, as illustrated more particularly in Figs. 4 and 6. In order to permit ready assembly, the 75 ends of the screen grid 3 are constructed as shown

in Fig. 7. The screen grid extension or flange 9 which serves also as a means of support, is fitted onto ring 10 with a push-fit so that it will make good electrical and mechanical contact. The end of ring 10 or the shoulder on the extension 9 may be split as shown at 10a so as to provide fingers having a certain amount of spring, thus further insuring good contact. The opposite end of the screen grid is provided with ring 10' as shown in Fig. 8 having split portions 10a' to resiliently engage the flange 9'. If desired, the center of the screen may be split to make assembly easy but care must be taken to provide good electrical and mechanical contact without impairing the shielding function. Screen grid terminals are shown at 11 and 11' spaced ninety degrees with respect to terminals 2a and 2a'.

20 The anodes 4 and 4' are cooled by the circulation of a cooling fluid through chambers 12 and 12' formed about the anodes by cylindrical members 13 and 13'. The cooling fluid passes into inlets 14 and 14' adjacent to the joints between the anodes and their insulating support members, thus insuring the air-tightness of the joints by keeping them cool. After passing around the 25 anodes, the cooling liquid is discharged at the outlets 15 and 15'. The anodes are supported by insulating cylindrical members 16, 16' and 17. Airtight joints are insured by the use of gaskets 18 and 18'. I have illustrated in Figs. 9, 10 and 11 30 various forms of airtight joints which may be employed.

35 Throughout the several assembly views of the tube of my invention, I have conventionally illustrated gaskets at each of the joints which are placed under compression for preventing the leakage of gas. To simplify the illustration of the invention, these gaskets have been illustrated schematically in the assembly views. However, I desire that it be understood that in practice, 40 the joints are formed with coacting faces establishing a serpentine course through the joint which substantially prevents undesirable leakage and provides a gas tight seal. Fig. 9 shows end plate 6 provided with an annular projection 6a which fits into a coacting annular recess 16a in the insulator 16. The gasket 18 which is disposed therebetween provides a substantial seal against the leakage of gas. Fig. 10 shows a modified construction in which end plate 6 is 45 provided with a pair of concentric ribs depending from end plate 6 as illustrated at 6b and 6c. These ribs fit into coacting annular recesses 16b and 16c in insulator 16. The gasket 18 which is 50 disposed between the ribs and the coacting recesses is deformed out of plane for establishing a gas tight seal. Fig. 11 shows a further modified form of seal in which end plate 6 has an annular projection 6d thereon having an echelon or offset annular face. The insulator 16 is 55 provided with a coacting face which is offset in steps or echelon formation as represented at 16d. The gasket 18, disposed between the echelon faces 6d and 16d, serves to prevent seepage of gas between the joints. As I have pointed 60 out, any one of the types of joint illustrated, or any other form of joint may be used for insuring a gas tight closure within the anode structure. The tube is held together by longitudinal support members 19 extending between the end 65 plates 6 and 6' and fastened by screws 20 and 20'.

70 It will also be understood that the tension members 19 have been illustrated schematically for the purpose of simplifying the illustration and that in practice, I employ any suitable ar- 75

5 arrangement of tension adjusting means for compressing the end plates 6 and 6' against the gaskets 18, insulators 16, gaskets 18', insulator 17 and insulator 16', and against the anodes 4 and 4'. One form of tension adjusting means has been illustrated in Fig. 12. In this arrangement, the rod 19 of insulation material has a sleeve 19a riveted thereto to provide an abutment against end plate 6'. The upper extremity of 10 rod 19 has a sleeve 19b riveted thereto, which sleeve is externally screw threaded to receive the engaging nut 25 by which end plate 6 and the associated insulators and anodes are maintained in airtight engagement. Various forms of turnbuckles may be employed, care being exercised to employ insulation means for reducing the distributed capacity effects. Anode terminals are provided at 21 and 21'. A connection for the 15 vacuum pump is shown at 22.

20 Suitable means are provided for governing the automatic operation of the vacuum pump for drawing that vacuum in the closed vessel of the tube for maintaining that degree of vacuum required for operation of the electron discharge 25 device.

25 By reason of the compactness of the construction used in this tube and the shortness of its electrical circuits, it can be used at much higher frequencies than can an ordinary tube or 30 two ordinary tubes in a push-pull circuit. The efficiency of the tube is greater than ordinary tubes at the limiting frequency of the latter. The arrangement of the screen grid provides excellent shielding and eliminates the use of balance circuits. The arrangement of terminals permits nearly ideal circuit design with respect to symmetry.

35 Figure 8 shows more clearly the arrangement of the ring member 9' which is secured to the end plate 6' of the demountable electron tube. The ring member 9' is insulatingly mounted with respect to the end plate 6' by means of spaced metallic supports represented at 9a' and 9b'. The metallic support 9a' is insulatingly mounted on pedestal insulator 26' supported on end plate 6'. The metallic support 9b' is insulatingly mounted on insulated terminal 11' and electrically connected with the connector which extends therethrough. The position of the pedestal insulator 26' and the screen grid terminal 11', in diametrically opposite relation, insures the rigid mounting of the screen grid within the demountable tube in concentric spaced relation to the other electrodes in the tube. The pedestal insulator 26' and insulated grid terminal 11' for the screen grid are offset ninety degrees with respect to the pedestal insulator 27' and the insulated control grid terminal 2a' on the end plate 6'. This arrangement insures complete insulation and rigid mechanical mounting of the several electrodes. The upper end structure of the tube is similarly arranged, that is, control grid 2 is supported by metallic strip members secured to pedestal insulator 27 and insulated terminal 2a', as represented in Fig. 4, while the screen grid is supported by strip members 9a connected to pedestal insulator 26 and strip member 9b connected to insulated terminal 11. The same diametrical spaced relation is maintained between the supports for the control grid and the supports for the screen grid, as heretofore explained with respect to the lower end of the tube.

70 The insulation material employed in the electron tube of my invention is formed of magnesium silicate or a combination of magnesium and

75 aluminum silicate which is compacted under high pressure and has such negligible porosity that there is no appreciable seepage of air through the insulation material. The insulation material may be machined to provide abutting joints of such character that leakage of air through the joint, particularly when a lead gasket is employed, is practically impossible. Furthermore, automatic control of the vacuum pump enables this pump to be operated at successive times for 10 maintaining the required vacuum in the tube.

15 The screen grid 3 is common to both sets of electrodes of the electron tube. As will be observed, the same cathode is employed for both sets of electrodes. There are pairs of control grids 15 and anodes associated with the cathode and the common screen grid is disposed intermediate the control grids and the anodes. This arrangement insures a highly compact construction for the 20 electron tube at the same time that the control grids of each of the electron tubes are effectively shielded. In the assembly process, control grids are insulatingly supported on the opposite end plates. These control grids are telescopically engaged by the intermediate insulator 7 during the 25 assembly of the tube. The screen grid is secured at its lower end by telescopic engagement between flange 9' and ring 10'. At the upper end, the ring 10, carried by the upper end plate 6, provides telescopic engagement with flange 9 30 carried by the screen grid, thereby centering the screen grid rigidly within the electron tube concentric with respect to the cathode, control grids and anodes. Sufficient space is provided by the aperture in the upper end plate 6 to insure the 35 manual alignment of the screen grid with respect to the control grids during the assembly process. The insulated pedestals which are provided between the end plates and the flanges 9 and 9' for insuring the firm mounting of the flanges 9 40 and 9' with respect to the end plates 6 and 6' for correspondingly facilitating the concentric engagement of the opposite ends of the screen grid with respect to the flanges 9 and 9' are so spaced as not to interfere with the manual adjustment 45 necessary for mounting a new filament in position. In all instances, the insulated pedestals which provide supports for the ends of the screen grid are offset from and maintained out of the path of the insulated pedestals which provide 50 supports for the control grids with respect to the end plates.

55 The assembly of the parts of the double tube of my invention is very practical in the form illustrated, but I fully appreciate that various modifications may be made by those skilled in the art and I intend no limitations upon my invention other than are imposed by the scope of the appended claims.

60 The invention herein described may be manufactured and used by or for the Government of the United States of America for Governmental purposes without the payment of any royalty thereon or therefor.

65 What I claim as new and desire to secure by Letters Patent of the United States is as follows:

1. A high power electron tube comprising a pair of end plates, alternately disposed insulating members and anodes stacked between said end plates, a replaceable cathode supported between 70 said end plates axially of said anodes, a plurality of control grids, one of said control grids insulatingly mounted on each of said end plates, insulation means interconnecting the intermediate ends of said control grids, a plurality of flanged 75

ring members, one of said ring members insulatingly mounted with respect to each of said end plates, and a screen grid detachably engageable with said ring members and disposed in concentric relation between said control grids and anodes.

2. A high power electron tube comprising a pair of end plates, alternately disposed insulating members and anodes stacked between said end plates, a replaceable cathode supported between said end plates axially of said anodes, a plurality of control grids, one of said control grids insulatingly mounted on each of said end plates, insulation means interconnecting the intermediate ends of said control grids, a plurality of annular supports, one of said annular supports insulatingly mounted adjacent the inside face of each of said end plates, and a cylindrical screen grid having its opposite ends detachably engaged with said annular supports whereby said screen grid is concentrically disposed with respect to said control grids and anodes.

3. A high power electron tube comprising a pair of end plates, alternately disposed insulating members and anodes stacked between said end plates, a replaceable cathode supported between said end plates axially of said anodes, a plurality of control grids, one of said grids insulatingly mounted on each of said end plates, insulation means interconnecting the intermediate

ends of said control grids, a plurality of flanged ring members, one of said flanged ring members insulatingly supported from the inside face of each of said end plates and disposed concentrically about the ends of said control grids, and a cylindrical cage-like screen grid having its opposite ends telescopically engaged over said ring members for removably mounting said screen grid in concentric relation to said control grids and anodes.

4. A screen grid electrode, means for demountably supporting the screen grid electrode, comprising a pair of perimetral supports to be mounted adjacent the inner faces of the end portions of an electron tube, the screen grid having its opposite ends detachably engaged with said perimetral supports, said perimetral supports having outwardly extending perimetral flanges thereon adapted to extend the effectiveness of the screen grid supported on said perimetral supports.

5. An electron tube comprising a cathode, a pair of control grid electrodes disposed end to end but insulated from each other and concentrically surrounding said cathode, an anode electrode individual to each of said control grid electrodes, and a screen grid electrode disposed between said pair of control grid electrodes and said anode electrodes and common to the two sets of control grid and anode electrodes.

LOUIS A. GEBHARD. 30
